CAMOUFLAGE NET

Adam F. Schuler, Gouverneur, N. Y., assignor to
Chester Lace Mills, Chester, Pa., a corporation
of Pennsylvania

Application March 11, 1943, Serial No. 478,848

11 Claims. (Cl. 87—4)

This invention relates to netting, and more especially to nets of the heavier types, such as those used as seines or as the foundation for military camouflage, stage scenery, etc.

One object of the present invention is to provide a net which can be made on wide vertical lace looms of the Nottingham or Levers types, which are normally employed in the manufacture of lace curtains or other lace strips, panels, etc.

Lace making machines of the above noted types are normally adapted to produce a plurality of strips, in a single vertical plane, simultaneously. However, these machines are capable of producing a single strip having a width equal to the sum of the widths of the total number of strips produced at any one time, with a maximum of three hundred and sixty inches.

Another object of the invention is to construct the net in such a manner that the strains on the "knots" of the net, attending the lateral spreading of the net in use, are borne by the heavier warp and spool threads of which the diverging strands of the net are composed, rather than by the much finer or lighter shuttle threads which tie groups of these heavier threads together, at the knots and throughout the extents of the divergent strands radiating from each knot.

The construction of the net of the present invention will be more fully disclosed hereinafter, reference being had to the accompanying drawings, of which:

Fig. 1 is a diagrammatic face view of a piece of the finished net, spread laterally;

Fig. 2 is an enlarged pictorial view of one of the "knots" of Fig. 1 with fragments of the diverging net strands radiating therefrom;

Fig. 3 is a diagrammatic view of a fragment of the net illustrating the warp and spool thread arrangement for producing the strands and "knots" of the net;

Fig. 4 is a diagrammatic view on a still larger scale of two of the net strands and a "knot" therebetween;

Fig. 5 is an edge view of the strand and knot structure shown in Fig. 4;

Fig. 6 is a diagrammatic cross-section through one of the strands at one of the knots, the section being taken on the line 6—6, Fig. 4; and

Figs. 7, 8 and 9 are views similar to Figs. 4, 5 and 6 respectively, of a modified form of shuttle-thread binding of the component threads of the net strands at and adjacent one of the "knots."

In general appearance, as shown in Fig. 1, the net of the present invention closely resembles the usual or ordinary cord netting, wherein

the meshes of the net are formed in horizontal rows or courses successively, with the cord of each course knotted to the cord of the next preceding and the next succeeding course respectively, throughout the length of the net.

In the present instance, the net is formed in a manner radically different from ordinary netting, in that the meshes of the present net are produced by a multiplicity of cords or threads hanging vertically and divided into a plurality of series respectively disposed in immediately adjacent parallel vertical planes. The cords or threads of the several series are alternately shogged laterally, right and left, while binding threads are passed to and fro between the laterally shogged main threads to tie groups of the main threads together, to form the strands of the net, and to tie adjacent strands together at staggered vertically spaced intervals to form the "knots" of the net.

For the purpose of illustration, in the present instance the strands generally, of which the net is composed, are designated as S, in Fig. 1, and the knots, or connections of the strands, are designated as K, while the meshes or interstices of the net are indicated at M.

For the purpose of description, the strands S are divided into two series S¹ and S², alternating across the width of the net.

Each strand S is composed of a plurality or group of threads or cords, and, in the present instance, these components are divided into three sub-series or sub-groups s¹, s², and s³ respectively, with one or more threads or cords constituting each sub-series, see Figs. 4, 5 and 6 particularly.

As shown in Fig. 4, for example, the sub-group s¹ occupies the front position, the sub-group s² occupies the back or rear position, and the sub-group s³ occupies an intermediate or center position in the strand.

As shown in Fig. 4, the component threads or cords s^{1-a} and s^{1-b} of the front sub-series s¹, and the component threads or cords s^{2-a} and s^{2-b} of the back sub-series s² are concurrently undulated, while the component threads or cords of the intermediate sub-series s³ are oppositely undulated and cross sub-series s¹ and s² at points 10, 10, spaced vertically along the lengths of the strands S, leaving open spaces 11, 11 in the composite strands S, between the oppositely outwardly bending short loops 12, 12 of the components of each sub-series s¹, s² and 13, 13 of the components of each sub-series s³.

As shown in Figs. 4 and 5, the components s^{1-a},

of the front sub-series s^1 , and the components s^{2-a} , of the rear series s^2 , are bound tightly together in side-by-side relationship, within the spaces 11, 11, by shuttle or binding threads B^1 , B^1 ; while the components s^{1-b} , of the front sub-series s^1 , and the components s^{2-b} , of the rear sub-series s^2 , are similarly bound tightly together in laterally abutting relationship within the spaces 11, 11, by binding threads B^2 , B^2 .

The tight lateral binding of the outside threads or cords s^{1-a} , s^{2-a} , s^{1-b} , s^{2-b} , pinches or snubs said outside threads or cords around the center or intermediate cords or threads s^3 , and prevents the loops 13, 13 of the cords or threads s^3 from being pulled between the loops 12, 12 of the aforesaid outside threads or cords, thus the component threads or cords of each composite strand S are bound together and collectively give great tensile strength to each strand.

In order to form the knots K, the threads or cords of the center sub-series s^3 of each strand S are provided with extra long loops or bights 13a, at spaced intervals therealong, which extend from one strand into and through an immediately adjacent strand to be bound in such adjacent strand in the same manner as the short loops 13 thereof.

As shown in Fig. 4, the long loops 13a of one strand S^1 extend into and through the next adjacent strand S^2 , and the long loops 13a of the strand S^2 extend into and through the first said strand S^1 , at corresponding spots along the two strands S^1 and S^2 .

Within the spaces 11a, 11a formed by the long loops 13a, 13a of the strands S^1 and S^2 , the number of wraps of the binding threads B^1 and B^2 , which normally secure the corresponding components of the front and back sub-series together in the spaces 11, 11, are increased to afford added resistance to any possible separation of the front and back sub-series s^1 , s^2 which would permit passage therebetween of the middle series s^3 under strains attending the lateral spreading of the net as a whole in use.

Thus, from the above it will be clear that the binding threads B^1 , B^2 are relieved of direct strains attending lateral spreading of the net, and these strains are transferred to the main threads or cords which constitute the components of the strands S by reason of the outside components of one strand being snubbed tightly, by the binding threads B^1 and B^2 , around the center components of the strands above and below the crossings of the intermediate components and the front and back components.

In that form of the invention shown in Figs. 7, 8 and 9, the binding threads B^3 embrace all of the components s^{1-a} , s^{1-b} , s^{2-a} , and s^{2-b} , of the face series s^1 and back series s^2 , in each of the spaces 11 and 11a, in effecting the snubbing of these components tightly around the components of the intermediate series s^3 , otherwise the construction is substantially the same as described in regard to the showings in Figs. 1 to 6 inclusive.

As shown in Fig. 3, the positions of the knots K are staggered in alternate spaces between hanging strand structures S, S, to produce the rectangular meshes M, M of the net, and it will be observed, in this regard, that the intermediate series s^3 , of each strand S shogs laterally from its parent strand to the right, to form a knot with a strand lying to the right of such parent strand, then to the left to form a knot with the strand lying to the left of such parent strand,

then to the right again, and so on alternately throughout the length of the net.

Obviously, the components s^{1-a} and s^{1-b} , may be replaced by a single strand. In a like manner, 5 a single strand may be used in place of the components s^{2-a} , s^{2-b} , and s^3 , as shown in Fig. 3, for example, for the purpose of simplicity of illustration, without departing from the spirit of the invention. In such instances, the binding ar-

10 rangement of Figs. 7, 8 and 9 would be employed. Similarly, single binding threads may be employed in place of the twin bindings B^1 , B^2 and B^3 .

It will be understood that the threads normally referred to in the lace making art as warp threads 15 may be used either as the face and back series or as the intermediate series, and that the spool threads may also be used in either place as desired.

The knots K may be made relatively open or 20 closed, as desired, by controlling the tension on the warp threads, or spool threads, or both during the manufacture of the net.

I claim:

1. A net comprising a multiplicity of laterally adjacent strands, a series of loops projecting laterally from predetermined strands and respectively passing between laterally separated parts of immediately adjacent strands at spaced intervals along the lengths of the strands, and binding threads securing said laterally separated parts of said adjacent strands together within the bights of said loops.

2. A net comprising a multiplicity of laterally adjacent strands, a series of loops projecting laterally from each strand and passing between laterally separated parts of immediately adjacent strands at spaced intervals along the lengths of the strands, and binding threads securing said laterally separated parts of said adjacent strands together within the bights of said loops.

3. A net comprising a multiplicity of laterally adjacent strands, a series of loops projecting laterally from the opposite sides of each strand and passing between laterally separated parts of immediately adjacent strands at spaced intervals along the lengths of the strands, and binding threads securing said laterally separated parts of said adjacent strands together within the bights of said loops.

4. A net comprising a multiplicity of laterally adjacent strands, a series of loops projecting laterally from the opposite sides alternately of each strand and passing between laterally separated parts of immediately adjacent strands at spaced intervals along the lengths of the strands, and binding threads securing said laterally separated parts of said adjacent strands together within the bights of said loops.

5. A net comprising a multiplicity of laterally adjacent strands, a series of loops projecting laterally from the opposite sides alternately of each strand and passing between laterally separated parts of immediately adjacent strands at spaced intervals along the lengths of the strands, with oppositely projecting loops of immediately adjacent strands effecting said passings at corresponding points along such strands, and binding threads securing said laterally separated parts of said adjacent strands together within the bights of said loops.

6. A net comprising a multiplicity of laterally adjacent strands each formed of a plurality of longitudinal components and arranged with one of the components of each of a number of predetermined strands formed into laterally extend-

ing loops and penetrating immediately adjacent strands between a pair of the longitudinal components thereof at spaced intervals along the lengths of the strands, and binding threads securing said pairs of components together within the bights of the penetrating loops respectively.

7. A net comprising a multiplicity of laterally adjacent strands each formed of a plurality of longitudinal components and arranged with one of the components of each strand extending laterally therefrom in the form of a loop at spaced intervals along the length of the strand and penetrating an immediately adjacent strand between a pair of the longitudinal components thereof, and binding threads securing said pair of strands together within the bights of the penetrating loops respectively.

8. A net comprising a multiplicity of laterally adjacent strands each formed of a plurality of longitudinal components and arranged with one of the components of each strand extending laterally therefrom at opposite sides alternately thereof in the form of a loop at spaced intervals along the length of the strand and penetrating an immediately adjacent strand between a pair of the longitudinal components thereof, and binding threads securing said pair of strands together within the bights of the penetrating loops respectively.

9. A net comprising a multiplicity of laterally adjacent strands each formed of a plurality of longitudinal components and arranged with one of the components of each strand extending laterally therefrom in the form of a loop with the loops staggered and projecting from opposite sides of the strand alternately at spaced intervals along the length of the strand and penetrating an immediately adjacent strand between a pair of the

longitudinal components thereof, and binding threads securing said pair of strands together within the bights of the penetrating loops respectively.

5 10. A net comprising a multiplicity of laterally adjacent strands each formed of a plurality of undulated longitudinal components, with the undulations of at least a pair of components in each strand bending oppositely to the undulations of at least another of the components of the strand, predetermined undulations of each strand being elongated laterally in the form of loops penetrating between pairs of components of immediately adjacent strands, and binding threads 15 wrapped around said pairs of components within the bights of the undulations and elongated loops thereof to bind said pairs together tightly within said bights throughout the length of each strand.

11. A net comprising a multiplicity of laterally adjacent strands each formed of a plurality of undulated longitudinal components, with the undulations of at least a pair of components in each strand bending oppositely to the undulations of at least another of the components of the strand, predetermined undulations of each strand being elongated laterally in the form of loops penetrating between pairs of components of immediately adjacent strands, and binding threads wrapped around said pairs of components within the bights of the undulations and elongated loops thereof to bind said pairs together tightly within said bights throughout the length of each strand, the wrappings of said binding threads being of greater numbers within the bights of said loops 25 than those within the bights of the other undulations.

30 35 ADAM F. SCHULER.
